GEORGE L. RICHARDSON AND JAMES C. MOODY, OF BRUNSWICK,
MAINE.

Letters Patent No. 92,471, dated July 13, 1869.

IMPROVEMENT IN PICKER-CUSHIONS FOR LOOMS.

The Schedule referred to in these Letters Patent and making part of the same.

To all whom it may concern:

Be it known that we, GEORGE L. RICHARDSON and JAMES C. MOODY, both of Brunswick, in the county of Cumberland, and State of Maine, have invented a new and useful Improved Picker-Cushion; and we hereby declare the following to be a full, clear, and exact description thereof, which will enable others to make and use our invention, reference being had to the accompanying drawings, forming part of this specification, in which—

Figure 1 is a bottom view of the metallic ring, showing the position of the nails thereof in dotted lines.

Figure 2 is a top view of a picker-cushion, with the metallic ring attached thereto.

Figure 3 is a side view of the same.

The use of leather in the construction of picker-cushions is quite extensive, and it is probably the best material for the purpose, the office of the cushion being to receive the end or point of the shuttle, and throw back the same. The difficulty in the use of this material, however, is, that the point of the shuttle gradually makes a hole in the leather, which hole is often irregular, or at one side of the centre of the cushion thus rendering it useless on account of its being burst or broken open, as described, before it is otherwise worn out.

We do not, of course, claim the leather cushion.

Our invention consists of a device for strengthening the cushion, fastening the different laminae of leather together, preventing it from bursting out at one side, and, by this means, enabling it to be used until worn quite or nearly through.

Our improvement consists of a ring of metal, having a flange on the inner circumference of the top or face

thereof; having, also, nails to penetrate the leather of the cushion, and two projecting parts, having nails also.

A is the ring.

a, its flange.

c, the nails.

d, the projections, also having nails.

The flange laps the leather on the face of the cushion.

The ring fits down over the outside of the cushion-edge.

The nails penetrate the cushion, and are clinched on the backside thereof.

The projections, with their nails, further secure the ring.

The ring itself is pressed or driven down, even with the face of the cushion.

The curved portion included within the ring, forms the cushion proper, and receives the shuttle-point. (See *b*, fig. 2.)

Thus the leather cushion is so strengthened and compacted, that it endures for much more time, and wears with more evenness.

What we claim as our invention, and desire to secure by Letters Patent, is—

The ring *A*, with flange *a*, nails *c*, and projections *d*, also having nails, when applied to a picker-cushion, as herein set forth.

GEORGE L. RICHARDSON.
JAMES C. MOODY.
